CONSOLE TABLE

Chester J. Barecki, Grand Rapids, Mich., assignor to
American Seating Company, Grand Rapids, Mich., a
corporation of Delaware

Filed June 21, 1966, Ser. No. 2,768

Term of patent 14 years

(Cl. D33—14)

FIG. 1

FIG. 2

FIGURE 1 is a perspective view of the console table showing the rear portion thereof and showing my new design; and

FIGURE 2 is a perspective view showing the front portion of the console table.

A dominant feature of the design lies in the top arrangement in which raised instrument panels are at the opposite ends of the front portion of the table top leaving therebetween an open area aligned with a compartment cover at the rear side of the table top.

I claim:

The ornamental design for a console table, as shown and described.
